Inventor:

Farnum F. Dorsey

UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

CONTACT SUPPORT FOR RELAYS.

Application filed August 27, 1923. Serial No. 659,566.

To all whom it may concern:

Be it known that I, FARNUM F. DORSEY, a citizen of the United States, residing at Rochester, in the county of Monroe and

5 State of New York, have invented certain new and useful Improvements in Contact Supports for Relays; and I do hereby declare the following to be a full, clear, and exact description of the invention, such as 10 will enable others skilled in the art to which it appertains to make and use the same.

This invention relates to means for supporting a contact in an electromagnetic instrument of the relay type.

15 In instruments of the type in question, particularly when used for regulating dynamo-electric machines, the contacts sometimes are made of carbon, with wide, flat faces, and in such cases it is desirable that the 20 contacts be so adjusted as to meet squarely throughout their cooperative surfaces. It has heretofore been proposed to secure this result by mounting one of the contacts with a spherical joint capable of universal angular adjustment; and the object of the present invention is to provide a contact-support in which this mode of adjustment is embodied in a simple, compact and effective manner.

30 To the foregoing end the invention consists in the contact-support illustrated in the accompanying drawings and hereinafter described, as it is defined in the annexed claims.

35 In the drawings, Fig. 1 is a side-elevation, partly in section, of a contact-support embodying the present invention, together with adjacent parts of the relay in which it is used, and Fig. 2 is a cross-section of the 40 contact-support on the line 2-2 in Fig. 1, looking upward.

The invention is illustrated as embodied in a relay having two carbon contacts, 5 and 6, of which the former is carried and 45 actuated by an armature 7. The contact 6 is embraced by a shell 8 drawn from sheet-metal, and the upper part of this shell has the form of a segment of a sphere, the center of curvature being located approximately 50 at the middle of the contact-face.

The shell 8 is seated on the concave lower surface of a head 9 formed at the lower end

of a stem 10. This stem is threaded through a terminal-block 11, which may be mounted in any convenient way on a stationary part 55 of the instrument.

The shell 8 is clamped to the head 9 by means of a bolt 12 which extends through an axial perforation in the stem 10. The shell 8 is centrally perforated to receive the bolt, 60 and the head 13 at the lower end of the bolt engages the inner surface of the spherical portion and clamps it firmly to its seat in the head 9, the parts being tightened and secured by a nut 14 on the upper end of the 65 bolt.

To prevent rotation of the bolt when the nut is turned, the head 9 is provided with a transverse slot, and a lug 15 is pressed out from the material of the bolt in position to 70 engage the slot. The slot has another valuable function, resulting from the fact that it divides the head into two parts capable of a slight relative springing movement. When the bolt is tightened the convex surface of the shell 8 springs these parts away from each other, and altho the movement is very slight it tends to secure a resilient pressure and frictional engagement between the parts by which loosening of the bolt in consequence of vibration or of thermal expansion and contraction is prevented.

The terminal block 11 is cleft horizontally and provided with a clamp-screw 16 by which it may be caused to clamp the stem 85 10 in adjusted position.

When the contacts are to be adjusted the screw 16 and the nut 14 are both loosened, and the contact 6 then automatically accommodates itself to the angle of the contact 5 90 under the influence of the spring-pressure of the armature. The stem 10 may then be screwed up or down, if required, to adjust the air-gap of the instrument. The screw 16 and the nut 14 are then tightened, thus 95 locking the parts in adjusted position.

The invention claimed is:

1. The combination, with a wide, flat contact, of a shell embracing the contact and having a spherically-curved, centrally-perforated rear portion; a stem axially perforated and provided with a head recessed to provide a seat for the spherical portion of the shell; and a bolt passing through the 100

perforations in the stem and the shell and having a head within the latter and a nut at the remote end of the stem.

2. A contact-support, as defined in claim 5 1, comprising, further, a terminal-block, in which the stem is threaded, provided with means for clamping the stem in adjusted position therein.

3. A contact-support, as defined in claim

1, in which said head is split to provide a 10 plurality of relatively yielding resilient portions.

4. A contact-support, as defined in claim 1, in which the head is transversely slotted and the bolt is provided with a lateral pro- 15 jection engaging the slot.

FARNUM F. DORSEY.
